ABSORPTION REFRIGERATION

Wilhelm Georg Kögel, Stockholm, Sweden, assignor to Aktiebolaget Electrolux, Stockholm, Sweden, a corporation of Sweden

Application May 1, 1948, Serial No. 24,545
In Sweden May 7, 1947

15 Claims. (Cl. 62—119.5)

1

My invention relates to absorption refrigeration systems in which provision is made for transferring liquid absorbent to a part of the system normally free of such absorbent to modify the normal operation of the system, such as, for example, to effect defrosting of the evaporator or cooling element.

It is an object of my invention to effect improvements in the manner in which liquid absorbent is transferred from the absorption liquid circuit to a higher located place in systems of this type, particularly to provide a new arrangement for raising such liquid by vapor lift or thermosiphon action in order to obtain better pumping as well as enable liquid to be raised through a relatively great height. More particularly, it is an object to provide such a new arrangement for raising liquid from the absorption liquid circuit to a higher located place in the system by a vapor lift tube or gas pump to which heat is supplied in a controlled manner at a relatively high temperature from a heating flue associated with the vapor expulsion unit of the refrigeration system. Further, it is an object to raise absorption solution relatively weak in refrigerant to a higher located place in the system by such a vapor lift tube or gas pump having provisions for supplying heat thereto when desired from the heating flue, preferably with the aid of a controllable heat transfer member, at a sufficiently high temperature to insure positive starting of the pumping action under all operating conditions encountered.

In accordance with my invention absorption solution to be raised to a higher located place in the refrigeration system is diverted from the absorption solution circuit to a region of a vapor lift tube or gas pump which is removed from the extreme lower end thereof, the portion or section of the lift tube projecting downwardly from the region absorption solution is supplied thereto serving as a liquid pocket adapted to receive heat from the heating flue of the vapor expulsion unit. Since heat is applied to the lower end of the heating flue constituting the heat input section which is at a higher temperature than other portions of the flue removed from the heat input end, the downwardly extending liquid pocket of the vapor lift tube is advantageously arranged to receive heat from such heat input section with the aid of the controllable heat transfer member. The heat transfer member may comprise an hermetically sealed heat transfer system containing a volatile fluid, such system having a lower vaporization portion heat conductively connected to the heat input section of the heating flue and within which the liquid pocket of the vapor lift tube is disposed, and an upper portion with-

2

in which the volatile fluid may be withheld from the vaporization portion or allowed to flow thereto when desired to initiate pumping of absorption solution from the absorption solution circuit to a higher located place in the system.

The novel features which I believe to be characteristic of my invention are set forth with particularity in the claims. The invention, both as to organization and method, together with the above and other objects and advantages thereof, will be better understood by reference to the following description taken in connection with the accompanying drawing forming a part of this specification, and of which the single figure more or less diagrammatically illustrates an absorption refrigeration system embodying the invention.

In the drawing I have shown my invention in connection with an absorption refrigeration system of a uniform pressure type which is well known in the art and in which an inert pressure equalizing gas is employed. Such a refrigeration system comprises a generator or vapor expulsion unit 10 including a boiler or pipe 11 containing a refrigerant, such as ammonia, in solution in a body of absorption liquid, such as water. Heat is supplied to the boiler 11 from a heating tube or flue 12 thermally connected therewith at 14, as by welding, for example. The heating tube 12 may be heated in any suitable manner, as by an electrical heating element disposed within the lower part of the tube 12 or by a liquid or gaseous fuel burner which is adapted to project its flame into the lower heat input end of the tube.

35 The heat supplied to the boiler 11 and its contents expels refrigerant vapor out of solution and such vapor passes upwardly from the vapor expulsion unit 10 through an air cooled rectifier 15 into an air cooled condenser 16 in which it is condensed and liquefied. Liquid refrigerant flows from condenser 16 through conduits 17 and 18 into a cooling element or evaporator 19 in which it evaporates and diffuses into an inert pressure equalizing gas, such as hydrogen, which enters through a conduit 20. Due to evaporation of refrigerant fluid into inert gas, a refrigerating effect is produced with consequent absorption of heat from the surroundings.

50 The rich gas mixture of refrigerant vapor and inert gas formed in cooling element 19 flows from the upper part thereof through a conduit 21, one passage of a gas heat exchanger 22, conduit 23 and absorber vessel 24 into the lower end of an absorber coil 25. In absorber coil 25 the rich gas mixture flows counter-current to downwardly flowing absorption liquid which enters through a conduit 26. The absorption liquid absorbs refrigerant vapor from inert gas, and inert gas weak

in refrigerant flows from absorber coil 25 in a path of flow including conduit 27, another passage of gas heat exchanger 22 and conduit 20 into the lower part of the cooling element 19.

The circulation of gas in the gas circuit just described is due to the difference in specific weight of the columns of gas rich and weak, respectively, in refrigerant vapor. Since the column of gas rich in refrigerant vapor and flowing from cooling element 19 to the absorber coil 25 is heavier than the column of gas weak in refrigerant and flowing from the absorber coil 25 to cooling element 19, a force is produced or developed within the system for causing circulation of inert gas in the manner described.

Absorption solution enriched in refrigerant flows from the absorber vessel 24 through a conduit 28 and an inner passage or pipe 29 of a liquid heat exchanger 30 which is disposed about the lower part of the vapor expulsion unit 10. The liquid flows from the inner pipe 29 of the liquid heat exchanger into the boiler 11 at a point which is at a level below the liquid level in the absorber 24 and below the liquid level of the column of liquid contained in the boiler. From the lower closed end of the boiler 11 liquid passes into the lower end of a lift tube or pump pipe 31 in thermal exchange relation with the heating tube 12 at 32, as by welding, for example.

Liquid is raised by thermosiphon or vapor-liquid lift action through pipe 31 to the upper part of a standpipe or riser 33 which is connected at its extreme upper end to an upper extension of the boiler 11 and at its lower end to the outer passage or pipe 34 of the liquid heat exchanger 30. Refrigerant vapor expelled out of solution in boiler 11, together with refrigerant entering the upper extension of the boiler from the standpipe or riser 33, flows upwardly from the vapor expulsion unit 10 to the condenser 16, as previously explained. The absorption liquid from which refrigerant vapor has been expelled flows from the standpipe 33 through the outer passage 34 of the liquid heat exchanger and conduit 26 into the upper part of absorber coil 25. The circulation of absorption solution in the liquid circuit just described is effected by raising of liquid through pipe 31.

The principal part of generated vapor produced in the vapor expulsion unit 10 is expelled from solution in boiler pipe 11, and liquid of decreasing refrigerant concentration flows downwardly in the boiler pipe to the bottom closed end thereof. In certain instances it is desirable to provide a thermal gap or air space 35 between the lower portion of the boiler pipe 11 and the heating tube 12. In this way excessive expulsion of refrigerant vapor from solution in the lower part of boiler pipe 11 is prevented, thereby avoiding undesirable decrease in concentration of the absorption solution and consequent increase in its temperature. In order to prevent excessive heating of the expelled vapors passing from the boiler pipe 11, the upper portion thereof is desirably thermally separated from the heating tube 12. As shown, the boiler pipe 11 diverges from the heating tube 12 at a level immediately above the level at which absorption solution is maintained in the boiler pipe. In this manner superheating of expelled vapor is avoided and rectification in the air cooled rectifier 15 is accomplished more effectively, so that a minimum quantity of vapor of absorption liquid will accompany refrigerant vapor passing to the condenser 16.

The parts of the generator or vapor expulsion

unit 10 just described and the liquid heat exchanger 30 are usually embedded in suitable insulating material contained within a metal shell having openings at the top and bottom thereof through which the open ends of the heating tube 12 project. In order to simplify the drawing, such an insulated enclosure for the vapor expulsion unit, which is well known in the art, has not been shown.

The outlet end of condenser 16 is connected by an upper extension of conduit 18, vessel 36 and conduit 37 to a part of the gas circuit, as at one end of gas heat exchanger 22, for example, so that any inert gas which may pass through the condenser 16 can flow into the gas circuit. Refrigerant vapor not liquefied in the condenser flows through the upper part of conduit 18 to displace inert gas in vessel 36 and force such gas through conduit 37 into the gas circuit. The effect of forcing gas into the gas circuit in this manner is to raise the total pressure in the entire system whereby an adequate condensing pressure is obtained to insure condensation of refrigerant vapor in condenser 16.

In order to increase the temperature of cooling element 19 when it is desired to melt frost which may accumulate thereon, provision is made, as will be explained presently, for raising warm absorption solution from the standpipe 33 through a riser conduit 38 into a conduit 39 from which the absorption solution flows by gravity into cooling element 19. In this manner rapid defrosting is effected due to the relatively high temperature to which the solution is heated in the vapor expulsion unit 10. The absorption solution passes from cooling element 19 through the gas heat exchanger 22 to the absorber vessel 24.

The conduit 38 constitutes a vapor lift tube or pump pipe through which absorption solution is raised when desired by heat derived from the heating flue 12 with the aid of a controllable heat transfer member. In the embodiment of the invention illustrated, the heat transfer member comprises a secondary heat transfer system including a vertically extending conduit or section 40 having the lower portion thereof in thermal exchange relation with the heating tube 12 at 41, as by welding, and a bulb or upper portion 42 flexibly connected at 43 to the upper end of the vertical section 40.

The heat transfer system is hermetically sealed and is charged with a volatile fluid substantially all of which is held in the bulb 42 when the latter is in the position shown in the drawing. When it is desired to effect defrosting of the cooling element 19, the bulb 42 is raised from the position shown, so that fluid will flow therefrom by gravity to the lower portion of the vertical section 40. The lower portion of the vertical section 40 constitutes the vaporization portion of the heat transfer system in which the fluid is vaporized by heat taken up from the heating tube 12. The vapor formed in the bottom of the vertical section 40 is partly condensed in such vertical section and gives up heat to the conduit 38 and its contents to raise absorption solution by thermosiphon or vapor lift action from standpipe 33 to the cooling element 19. Such lifting of absorption solution continues until all of the vapor is condensed in the bulb 42 which previously has been returned to its lower position shown in the drawing. In this way substantially all of the volatile fluid is held back from the lower vaporization portion of the vertical section 40, and heat transfer to the conduit 38 at a sufficient rate

to cause raising of solution therein is terminated. In accordance with my invention, in order to effect improved pumping and lifting of absorption solution in the lift tube or pump pipe 38, the lower end thereof is connected by a conduit 44 to the standpipe 33, and the lift tube 38 in effect is extended downwardly from the region conduit 44 communicates with the standpipe 33 by a pipe section 45 which is closed at its lower end and forms a dead-end liquid pocket. The dead-end liquid pocket 45 projects downwardly from the highest point of the liquid heat exchanger 30 and is adapted to receive heat from the heating flue 12. In the preferred embodiment of the invention shown, the pipe section 45 is disposed within the lower portion of the vertical section 40 of the heat transfer system which can be rendered operable, when desired, for effectively utilizing the heating flue 12 to supply heat to the lower extended portion or pipe section 45 of the lift tube 38.

During normal operation of the refrigeration system when a source of heat is applied to the lower heat input section of the heating flue 12 and cooling element 19 is producing a refrigerating effect, the pipe section 45 contains absorption solution which is relatively weak in refrigerant and flows therein through the conduit 44 from the lower end of standpipe 33. Since the lower portion of the vertical section 40 of the heat transfer system is heat conductively connected at 41 to the heating flue 12, the lower end of the vertical section 40 becomes heated and heat is radiated from the inner wall surface thereof to the pipe section 45. Such heating of the pipe section 45 by radiated heat is insufficient to render the lift tube 38 operable to raise solution by vapor lift action. However, the radiated heat is taken up by the pipe section 45 and the concentration of refrigerant in the absorption solution therein gradually becomes reduced due to such heating. When the same body of absorption solution in the pipe section or pocket 45 is held therein for a sufficiently long interval of time and not displaced or replenished by other absorption solution during periods when the pump pipe 38 is ineffective to raise solution therethrough, the liquid in the pipe section 45 may eventually have such a low concentration of refrigerant that it consists substantially entirely of absorption liquid.

When it is desired to raise warm absorption solution from the standpipe 33 into the cooling element 19, the bulb 42 is raised to cause the volatile fluid therein to flow to the bottom of the vertical section 40 of the heat transfer system. The volatile fluid is vaporized by heat supplied by the heating flue 12, and heating of the liquid in the pocket 45 will take place at a sufficiently rapid rate to bring such liquid to its boiling temperature even when the liquid is substantially entirely absorption liquid alone. At the same time heat is supplied at a sufficiently rapid rate to the lift tube 38 and solution therein to cause expulsion of vapor and effect raising of warm absorption solution therein by thermosiphon or vapor lift action into conduit 39 from which the raised solution flows by gravity into cooling element 19 to effect rapid defrosting.

By providing the pocket 45 which extends downwardly from the highest point of the liquid heat exchanger 30 adjacent the region from which absorption solution is diverted into the pump pipe 38, and utilizing such pocket as a downward projection of the pump pipe itself, sev-

eral advantages are realized. In the first place, the pocket 45 is disposed adjacent the lower heat input end of the heating flue 12 at which region heat can be supplied at the highest possible temperature to the pocket and liquid held therein. Secondly, since the pocket is in alignment with the pump pipe 38 and serves as a downward extension thereof, the vapor bubbles formed therein and rising into the lower end of the pump pipe acquire substantial velocity, thereby promoting lifting of liquid in the pump pipe by vapor lift or thermosiphon action. In effect, the pipe section 45 acts to increase the actual reaction head under which solution is raised in the pump pipe 38 and creates an effective reaction head of greater height which not only produces more rapid pumping of solution but also enables the solution to be raised to a higher lever. This is particularly advantageous in an embodiment of the invention like that shown and just described in which the warm absorption solution raised to a higher level is relatively weak in refrigerant and hence requires heating at a higher temperature than absorption solution relatively rich in refrigerant to establish effective pumping of liquid by vapor lift action.

Further, by providing the downwardly extending liquid pocket 45 and locating such pocket at the same level or elevation at which heat is taken up from the heating tube 12 by the controllable heat transfer member, heat is transferred more or less directly to the pump with the aid of the pipe section or liquid pocket 45. All of the vapor bubbles formed in the liquid pocket 45 and passing upwardly therefrom are not only effectively utilized to raise solution by vapor lift action in the pump pipe 38, but also utilized to expel refrigerant vapor from solution in the parts of the pump pipe 38 located above the region conduit 44 is connected thereto, so that the pumping action will be improved. This is so because the vapor bubbles of absorption liquid passing from the pocket 45 into the pump pipe 38 rise into lower temperature regions in which such vapor bubbles often collapse and condense, and the heat of condensation thus liberated is effectively utilized to cause expulsion of refrigerant vapor from absorption solution which enters the pump pipe through the conduit 44 and the refrigerant concentration of which is higher than that of the liquid in the pocket 45.

Modifications of the embodiment of my invention which I have described will occur to those skilled in the art, so that I desire my invention not to be limited to the particular arrangement set forth. Thus, a heat transfer member of a type different from the secondary heat transfer system shown and described above may be employed to supply heat from the heat flue at will and when desired to the liquid pocket 45. Therefore, I intend in the claims to cover all those modifications which do not depart from the spirit and scope of my invention.

What is claimed is:

1. In an absorption refrigeration system having a plurality of interconnected parts, a heating flue having a lower heat input end, a circuit for absorption solution comprising parts including a liquid heat exchanger, a boiler element and a first vapor lift tube, said element and said first lift tube being in thermal contact with said heating flue, said heating flue and element having portions projecting downwardly from the highest point of the liquid heat exchanger, connecting means for conducting absorption solution from

said circuit to a higher located part in said system including a second vapor lift tube connected to receive absorption solution at one region and deliver raised solution to said higher located part, and said second lift tube having a portion projecting downwardly from said solution receiving region which is adapted to receive heat from the downwardly projecting portion of said heating flue, the portion of said second lift tube extending above said solution receiving region being arranged to receive substantially all of the vapor formed in the downwardly projecting portion of said second lift tube and passing upwardly therefrom.

2. In an absorption refrigeration system having a plurality of interconnected parts, an upright heating flue having a lower heat input end, a circuit for absorption solution comprising parts including a liquid heat exchanger, a boiler vessel and a first vapor lift tube, said vessel and first lift tube being in thermal contact with said heating flue, said heating flue and vessel having portions projecting downwardly from the highest point of the liquid heat exchanger, connecting means for conducting absorption solution from said circuit to a higher located part in said system including a second vapor lift tube connected to receive absorption solution at one region and deliver raised solution to said higher located part, said second lift tube having a portion which projects downwardly from said solution receiving region, and structure operable to alter the thermal connection of the downwardly projecting portion of said second lift tube and the downwardly projecting portion of said heating flue.

3. In an absorption refrigeration system having a plurality of interconnected parts, a heating flue having a lower heat input end, a circuit for absorption solution comprising parts including a liquid heat exchanger, a boiler pipe and a first vapor lift tube, said pipe and first lift tube being in thermal contact with said heating flue, said heating flue and boiler pipe having portions projecting downwardly from the highest point of the liquid heat exchanger, connecting means for conducting absorption solution from said circuit to a higher located part in said system including a second vapor lift tube connected to receive absorption solution at one region and deliver raised solution to said higher located part, said second lift tube having a portion projecting downwardly from said solution receiving region, and a secondary heat transfer system constructed and arranged to supply heat when desired from the downwardly projecting portion of said heating flue to the downwardly projecting portion of said second lift tube.

4. A system as set forth in claim 3 including means embodied in said secondary heat transfer system for manually initiating operation thereof and automatically stopping operation thereof after an interval of time.

5. A system as set forth in claim 3 in which said secondary heat transfer system comprises an hermetically sealed structure containing a volatile heat transfer agent having an upper condenser portion and a lower vaporization portion, said lower portion being thermally connected to said flue and having the downwardly projecting portion of said second lift tube disposed therein and spaced therefrom.

6. In an absorption refrigeration system having a plurality of interconnected parts, a heating flue having a lower heat input end, a circuit for absorption solution comprising parts including a

boiler vessel and a first vapor lift tube thermally connected to said flue to cause expulsion of refrigerant vapor from solution and raise solution to promote circulation of solution in said circuit, connecting means for conducting absorption solution from said circuit to a higher located part in said system including a second vapor lift tube which is closed at its lower end and connected to receive solution from said circuit at a region removed from and above such closed end and deliver raised liquid to said higher located part, the portion of said second lift tube between the solution receiving region and the lower closed end thereof being adapted to be heated by said heating flue.

7. In an absorption refrigeration system having a plurality of interconnected parts, an upright heating flue having a lower heat input end, a circuit for absorption solution comprising parts including a boiler element and a first vapor lift tube thermally connected to said flue to cause expulsion of refrigerant vapor from solution and raise solution to promote circulation of solution in said circuit, connecting means for conducting absorption solution from said circuit to a higher located part in said system including a second vapor lift tube which is closed at its lower end and connected to receive solution from said circuit at a region removed from and above such closed end and deliver raised liquid to said higher located part, the portion of said second lift tube between the solution receiving region and the lower closed end thereof being disposed adjacent the lower heat input section of said heating flue, and structure operable to alter the thermal connection of the last-mentioned portion of said second lift tube and the lower heat input section of said heating flue.

8. In an absorption refrigeration system having a plurality of interconnected parts, a heating flue having a lower heat input section, a circuit for absorption solution comprising parts including a boiler vessel and a first vapor lift tube thermally connected to said flue to cause expulsion of refrigerant vapor from solution and raise solution to promote circulation of solution in said circuit, at least said first lift tube being thermally connected to the lower heat input section of said flue, connecting means for conducting absorption solution from said circuit to a higher located part in said system including a second vapor lift tube which is closed at its lower end and connected to receive solution from said circuit at a region removed from and above such closed end and deliver raised liquid to said higher located part, the portion of said second tube between the solution receiving region and the lower closed end thereof forming a dead-end liquid pocket, at least the portion of said second lift tube forming said pocket being adapted to receive heat from the lower heat input section of said flue.

9. In an absorption refrigeration system having a plurality of interconnected parts, a heating flue having a lower heat input end, a circuit for absorption solution comprising parts including a boiler element and a first vapor lift tube thermally connected to said flue to cause expulsion of refrigerant vapor from solution and raise solution to promote circulation of solution in said circuit, connecting means for conducting absorption solution from said circuit to a higher located part in said system including a second vapor lift tube which is closed at its lower end and connected to receive solution from said circuit at a region removed from and above said closed end

and deliver raised liquid to said higher located part, the portion of said second tube between the solution receiving region and the lower closed end thereof forming a dead-end liquid pocket, said pocket having a cross-sectional area large enough to permit free relative movement of vapor and liquid therein and the portion of said second lift tube above the solution receiving region having a cross-sectional area small enough to prevent free relative movement of vapor and liquid therein, at least the portion of said second tube forming said pocket being adapted to receive heat from said heating flue.

10. A system as set forth in claim 6 in which said second lift tube is connected to receive absorption solution weak in refrigerant.

11. A system as set forth in claim 6 in which the principal part of the refrigerant vapor expulsion is effected in said boiler vessel and said second lift tube is connected to receive absorption solution from said circuit after the solution is deprived of refrigerant in said boiler vessel.

12. In an absorption refrigeration system having a plurality of interconnected parts, a heating flue having a lower heat input end, a circuit for absorption solution comprising parts including a boiler vessel and a first vapor lift tube thermally connected to said flue to cause expulsion of refrigerant vapor from solution and raise solution to promote circulation of solution in said circuit, connecting means for conducting absorption solution from said circuit to a higher located part in said system including a second vapor lift tube which is closed at its lower end and connected to receive solution from said circuit at a region removed from and above such closed end and deliver raised liquid to said higher located part, the portion of said second lift tube between the solution receiving region and the lower closed end thereof being disposed alongside the portion of said first lift tube thermally connected to said heating flue and also adapted to receive heat therefrom.

13. In an absorption refrigeration system having a plurality of interconnected parts including a cooling element, a heating flue having a lower heat input end, a circuit for absorption solution comprising parts including a boiler vessel and a first vapor lift tube thermally connected to said flue to cause expulsion of refrigerant vapor from solution and raise solution to promote circulation of solution in said circuit, connecting means for conducting absorption solution from said circuit to said cooling element including a second vapor lift tube for pumping solution through a greater height than that in said first lift tube, said second lift tube being closed at its lower end and connected to receive solution from said circuit at a region removed from and above such closed end and deliver raised liquid to said cooling element, the portion of said second lift tube between the solution receiving region and the lower closed end thereof being adapted to receive heat from said heating flue.

14. In an absorption refrigeration system having a plurality of interconnected parts including a cooling element, an upright heating flue having a lower heat input end, a circuit for absorption solution comprising parts including a liquid heat exchanger for conducting solution in a generally vertical direction therethrough, a boiler vessel and a first vapor lift tube, said vessel and first lift tube being thermally joined to said heating flue to cause expulsion of refrigerant vapor from

solution and raise solution by vapor lift action to promote circulation of solution in said circuit, said flue and vessel having portions projecting downwardly from the highest point of the liquid heat exchanger, connecting means for diverting absorption solution from said circuit to said cooling element including a second vapor lift tube connected to receive absorption solution at one region and deliver raised solution to said cooling element, said second lift tube having a portion which projects downwardly from said solution receiving region, and means for supplying heat from the downwardly projecting portion of said flue to the downwardly projecting portion of said second lift tube, the portion of said second lift tube extending above said solution receiving region being arranged to receive substantially all of the vapor formed in the downwardly projecting portion of said second lift tube and passing upwardly therefrom.

15. In an absorption refrigeration system of the inert gas type having a plurality of interconnected parts, an upright heating flue having a lower heat input end, a circuit for absorption solution including a liquid heat exchanger having several passages for conducting solution in a generally vertical direction therethrough and a vapor expulsion unit comprising first and second conduits and a first vapor lift tube, at least one of said conduits being thermally connected to said flue, said first conduit and flue projecting downwardly from the highest point of said heat exchanger, said first conduit being closed at its lower end and connected to receive absorption solution from a passage of said liquid heat exchanger at a region removed from and above such closed end, said first lift tube being thermally joined to said flue and connected to receive absorption solution from the lower part of said first conduit and deliver raised solution to the upper part of said second conduit which is in communication with another passage of said liquid heat exchanger, connecting means for conducting absorption solution from said circuit to a higher located part in said system including a second vapor lift tube connected to receive absorption solution from said second conduit at one region and deliver raised solution to said higher located part, said second lift tube having a portion which projects downwardly from said solution receiving region, and means for supplying heat from the downwardly projecting portion of said flue to the downwardly projecting portion of said second lift tube, the portion of said second lift tube extending above said solution receiving region being arranged to receive substantially all of the vapor formed in the downwardly projecting portion of said second lift tube and passing upwardly therefrom.
